UNITED STATES PATENT OFFICE

150,889

DESIGN FOR A KEY OR THE LIKE

Walter F. Rothe, Washington, D. C.

Application September 6, 1946, Serial No. 133,113

Term of patent 14 years

(Cl. D50—4)

To all whom it may concern:

Be it known that I, Walter F. Rothe, a citizen of the United States of America, residing in Washington, District of Columbia, have invented a new, original, and ornamental Design for a Key or the like, of which the following is a specification, reference being had to the accompanying drawing, forming part thereof.

The characteristic features of my design reside in the portion shown in full lines.

I claim:

The ornamental design for a key or the like, substantially as shown and described.

WALTER F. ROTHE.
